UNITED STATES PATENT OFFICE.

LAURENCE MARX, OF NEW ROCHELLE, NEW YORK, ASSIGNOR TO COHN-HALL-MARX CO., OF NEW YORK, N. Y., A CORPORATION OF NEW YORK.

SPECIAL TEXTILE-FABRIC PACKAGE.

Application filed December 18, 1922. Serial No. 607,732.

To all whom it may concern:

Be it known that I, LAURENCE MARX, a citizen of the United States, and resident of New Rochelle, in the county of Westchester, and State of New York, have invented 5 certain new and useful Improvements in Special Textile-Fabric Packages, of which the following is a specification.

My invention relates to a said package and

10 method of packing, distributing and vending merchandise and especially textiles such as shirtings, dress goods and other fabrics which are made and sold in a great variety of styles, colors, grades or patterns.

15 Full size rolls or bolts of fabrics as produced at the mills, in accordance with the present method of distribution, are shipped to distributors or jobbers. The larger retail merchants order the fabrics from the jobbers in whole bolts and the volume of their business justifies the large investment necessary for the purchase of a suitable assortment of these long pieces. Considerable loss is involved in the handling of the bolts since

20 there is no adequate or convenient way of keeping the fabrics clean and they frequently become soiled, especially at the edges, in the repeated handling of the bolt as the material is sold in short pieces. The last few yards

25 wound close to the cloth-board are also usually very much crumpled or wrinkled and present a bad appearance even when clean. For these and other reasons a large number of ends or remnants accumulate

30 which must be sold at reduced prices. The smaller retail merchants on account of the smaller volume of their business may buy a certain number of full pieces but are not justified in the large investment required for

35 a large assortment of the full pieces, and for this reason, especially in the more expensive fabrics, they frequently order short pieces say from 10 to 20 yards, and the jobber or other distributor is required to take off from the bolts, measure and cut and re-

40 roll these short pieces with considerable risk of soiling or mudding them, and with a large labor cost and other overhead charges. The handling of these small pieces or bolts

45 by the retailer involves the same difficulties as in the case of the large bolts except for the smaller investment involved. The small pieces frequently become soiled, remnants accumulate and losses are involved as in the

50 case of the larger merchants handling full

bolts. Heretofore no satisfactory means or method has been proposed or adopted so far as I am aware to overcome the above and other difficulties and disadvantages in the present method of distribution and sale of fabrics. My invention provides a method which overcomes these difficulties and has additional and novel advantages as herein-after set forth.

The general object of the invention is to 65 provide a suitable package and a method by which a retail merchant may be furnished with a desirable variety of fabrics of a certain class so that he is enabled to suit the preferences of his customers without carrying in stock a corresponding number of full sized bolts of the fabric. Another object is to provide a package and a method which are adaptable to the direct supply of retail dealers and is equally adaptable to distribution through jobbers or wholesalers, and is in general adapted or adaptable to the present trade customs in the textile industries.

To attain these and other objects the invention method comprises, in brief, the folding or rolling of textile fabrics, for example, shirtings or dress goods in small rolls or bolts, each bolt usually consisting of a piece much shorter than the full bolt length and the length of the piece usually being calculated to provide a predetermined number of dress or shirt "patterns." The small bolts are preferably thin and flat so that they may be piled compactly in flatwise relation. When desired, a cloth board, usually thinner 90 than the ordinary "board," may be used as a center for the small bolt, or this may be omitted.

A suitable number of the small pieces or bolts, usually of different patterns or grades 95 to provide a desirable assortment, are placed together flatwise forming a rectangular pile, and this pile of bolts is enclosed in a suitable container which is usually a display container adapted when closed to completely cover 100 and protect the goods from dust or dirt and also adapted to be readily opened to display the goods and usually having a movable cover and a "drop" front so that the container can be quickly and easily thrown open to display the goods to customers. A number of the containers, each enclosing a plurality of bolts, may be packed and shipped in one case, but more desirably each container filled as described is placed in an in- 110

dividual shipping case or carton in which it is shipped direct to the retailer, or a plurality of the individual packages are shipped to a wholesaler for distribution by him to retailers without the necessity for opening the containers when they are suitably marked to indicate the nature of the contents.

In this way a retail dealer, and especially one doing a small business, is enabled to place before his customers a variety of goods which may be equal to that displayed in the larger stores without the necessity for a large investment in full bolts or pieces of fabric, and loss and inconvenience resulting from soiling and the accumulation of remnant ends incident to the handling of full bolts.

The characteristics and advantages of the invention are further sufficiently explained in connection with a detail description of the method with reference to the accompanying explanatory drawings in which:

Figure 1 is a perspective view of suitable blanks for the production of an inner or display container in one form suitable for the present method.

Figure 2 is a perspective view of the container body.

Figure 3 is a cross section of the complete container properly filled with goods and opened for display.

Figure 4 is a perspective view of the same.

Figure 5 is a perspective view of the container closed.

Figure 6 is a perspective view of an outer container or shipping case open to receive an inner container.

Figure 7 is a perspective view of the same closed and sealed.

Figure 8 is a section at 8—8, Figure 7.

Figure 4 shows a plurality of relatively short pieces of fabric, such as shirting, of different designs or patterns arranged in flat rolls or bolts B, these bolts being piled flatwise together and enclosed in a suitable display container C. The bolts may or may not be formed upon "board" centers b. When such "boards" are used they may be thinner than boards used for standard bolts. The material and design or construction of the container may vary greatly, but in a desired form it comprises a main or body part 1 having a bottom 2, end walls 3, narrow front walls 4, (which may be omitted in some cases), and a back wall 5, and having an open top and also having the main front portion open between the inward edges of the short front wall 4. A top cover 6 is hingedly connected at the upper edge of the back wall 5 and desirably this top cover has a front flange 7 and end flanges 8. The front cover 9 is hingedly connected to the front edge of the bottom 2, this front cover being arranged to fold up and close the front

opening and to be secured by the front flange 7 of the top cover 6 as shown in Fig. 5. Desirably the short pieces or bolts are secured in the container or tied together with ribbons or tapes 10 although these may be omitted in some cases.

In one particular embodiment, the container may be of card- or fiber-board of suitable grade and stiffness, and as shown in Fig. 1 the material for each container may be cut in the form of three originally separate blanks one of which includes the top-cover 6 with its flanges or flaps 7 and 8, another the bottom 2, back 5, ends 3 and front wall members 4, and the other blank constitutes the front wall 9; otherwise the blank may be originally cut as a unit and the parts then separated as also sufficiently indicated in Fig. 1. The back wall portion 5 may have skived or beveled end flaps 5^a which are folded and adhesively connected to end walls 3 when blank-section 1 is "set up" as shown in Fig. 2, producing substantially smooth inner end wall surfaces. The top cover is then hingedly connected to back wall 5, conveniently by means of strips 6^a of fabric or paper, and the front wall 9 is connected to the front edge of bottom 2 by similar hinge strips 9^a. When desired, any or all of the outer or inner surfaces of the container may be covered with fabric or paper of suitable grade and "finish", to strengthen the structure or for decorative effect. Straps or tapes 25 may be provided to support top 6 in open position.

When the container is closed, as shown in Fig. 5, the contents are completely covered and protected from soiling or other damage. A number of these filled containers may be packed and shipped together without individual coverings; but more desirably each

filler container with its varied assortment of fabrics is placed in an outer container or shipping case S, Figures 6 to 8. These cases or cartons may vary greatly in construction but in one desirable form they may be of corrugated "board" as shown, arranged to open along one side or at one end, and specifically, as shown in the present example, the carton is provided at one end with pairs of opposite foldable flaps 15 and 16 which are folded down after the inner container is inserted and secured in any suitable way, conveniently by means of strips of adhesive paper 17 and the carton may also be reinforced at other points or along other edges by additional adhesive strips such as 18 and 19. The shipping case reinforces and protects the inner container and especially prevents any soiling of the inner container which would render it unsuitable for display in the retail shop.

A label such as 20 may be placed on the outside of the shipping case when desired and this label may be suitably marked to

5 indicate the nature of the contents; for instance, the label as shown in Figure 7 is marked "Assortment No. ____" which will serve to identify the contents by reference to a list which may be furnished by the manufacturer or distributor who packs the goods.

10 A suitable number of the individual packages, containing any desired number of different goods assortments, is furnished to wholesalers or jobbers, and when, as is preferred, each of the inner containers is enclosed in an outer container or shipping case S, it is unnecessary for the jobber to 15 open the outer case or to otherwise handle the goods, but the packages may be handled and reshipped as units to the retail dealer on his order without any possibility of soiling the fabrics while they are in the 20 hands of the jobber and with a minimum handling cost.

25 When one or more of the units is received by the retailer the outer container is quickly and easily opened and the inner container with its contents may be placed on a shelf closed, or it may be placed on a shelf with the front side outward, with the top cover 6 closed and with the front cover 9 dropped to disclose the edges of all the 30 bolts B for selection by purchasers, or the container may be placed on a counter or show-case top with the top cover 6 thrown back and the front cover dropped as shown in Figure 4.

35 One piece or bolt at a time may be easily slipped out from the pile of bolts B without disturbing the others, and for that purpose the narrow front walls 4 when provided are made outwardly bendable, and when 40 a piece has been cut off the bolt may be easily slipped back into the pile or placed on top. The assortment of fabrics is displayed in such a way that customers may easily make a selection without the necessity for much or any handling and soiling 45 of the goods, and in addition the described method of arranging the assortment in display boxes permits a more attractive exhibition of the goods and permits more varieties of fabrics to be displayed in reasonable space and for a smaller investment 50 than has heretofore been possible.

55 When a number of the display containers are placed on view in the store they may be easily closed in a very short time, for instance, when the store is being put in order for the night, by simply turning up the front covers and dropping the top covers in place, and the goods are then completely protected from any damage until it 60 is desired to again display them.

65 The retail merchant and especially the small dealer, is therefore able for a given expenditure to place before his customers a much greater variety of fabrics than has

heretofore been possible, and he is also relieved to a great extent from losses on account of soiling, crumpling, ends and remnants and in fact all the disadvantages of the present methods, pointed out above, are 70 avoided.

The disadvantages to the jobber involved in established methods as also above pointed out, are avoided, with accompanying positive advantages also sufficiently explained above, and the importance of the invention to jobbers is emphasized by the fact that the majority of jobbers' customers are small retailers so that the bulk of the jobbers' output may be handled in accordance with the invention method, with corresponding profits and advantages.

The invention is of great advantage to individual consumers, for it enables those who have access only to smaller retailers to 85 select from a much greater variety of fabrics, and this in turn tends to retain local patronage for the small dealer.

I claim:

1. A textile fabric package comprising a 90 plurality of lengths of fabric each much shorter than the conventional bolt, each length folded into a rectangular bolt of fabric, the respective bolts of fabric differing from one another to provide a varied 95 assortment and the bolts being piled one upon another to form a package of a size easily handled, and a dust proof casing normally enclosing and snugly fitting around the pile of bolts in which the latter are 100 arranged lengthwise, said casing having a movable wall whereby when the same is moved to open position a longitudinal edge of each bolt of the pile of bolts will be exposed so that all of the fabrics may be 105 readily inspected and a selection made and the selected bolt removed without removing the other bolts of the pile and whereby said movable wall may then be moved to closed 110 position to protect the remaining bolts.

2. A textile fabric package comprising a plurality of lengths of fabric each much shorter than the conventional bolt, each length folded into a rectangular bolt of fabric, the respective bolts of fabric differing from one another to provide a varied assortment and the bolts being piled one upon another to form a package of a size easily handled, and a dust proof casing normally enclosing and snugly fitting around the pile of bolts, in which the latter are arranged lengthwise, said casing having a movable wall whereby when the same is moved to open position a longitudinal edge of each bolt of the pile of bolts will be exposed so that all of the fabrics may be readily 120 inspected and a selection made and the selected bolt removed without removing the other bolts of the pile and whereby said movable wall may then be moved to closed 125 position to protect the remaining bolts.

position to protect the remaining bolts, and a removable outer container of stout material securely enclosing the display receptacle and its contents and adapted to protect the receptacle and contents in shipment.

3. A special package for displaying and merchandising fabrics put up in bolts of relatively short fabric lengths, affording a varied assortment of fabrics in compact and 10 easily handled form, said package consisting of a relatively long and narrow receptacle of substantially the length and width, and of a height adapted to contain a plurality of thin bolts, said receptacle containing a plurality of superposed short length bolts of assorted textile fabrics arranged lengthwise therein, said receptacle having a closure member adapted to be moved to expose longitudinal edges of the 15 said superposed bolts, and to provide an opening through which the bolts may be removed and replaced as desired, and also adapted when closed to protect the fabrics from soiling, the construction and arrangement being such that the entire package may be easily handled and moved from shelf to counter and thrown open for the display of the goods and ready selection thereof by purchasers without removal of the bolts 20 from the receptacle.

4. A textile fabric package comprising a plurality of lengths of fabric, each much shorter than the conventional bolt, each length folded into a rectangular, flat bolt 25 of fabric, the respective bolts of fabric differing from one another to provide a varied

assortment and the bolts being arranged in flat-wise contact to form a group of a size easily handled, and a dust-proof casing normally enclosing and snugly fitting around the group of bolts in which the latter are arranged lengthwise, and closure means for the casing operable from a closed to an open position and when in the latter position exposing an endmost bolt of the group and 40 also exposing longitudinal edges of all the bolts, so that all of the fabrics may be readily inspected and a selection made and the selected bolt removed without removing the other bolts and whereby said closure 45 means may then be moved to closed position to protect the bolts.

5. A textile fabric package comprising a plurality of lengths of fabric, each fabric-length being much shorter than that of the 50 conventional bolt, each length folded into a rectangular, flat bolt of fabric, the respective bolts of fabric differing from one another to provide a varied assortment and the bolts being arranged in flatwise contact 55 to form a group of a size easily handled, and a display casing normally enclosing and snugly fitting around the pile of bolts in which the latter are arranged lengthwise, the casing being constructed to display 60 longitudinal edges of the bolts and having a closure operable to permit removal of a selected bolt.

Signed at city of New York in the county of New York and State of New York this 70 9th day of December, A. D. 1922.

LAURENCE MARX.
